R. S. PEIRCE

PIPE CLAMP

Filed Oct. 11, 1920

Inventor:
Ralph S. Peirce

By J. L. Clegg Atty.

UNITED STATES PATENT OFFICE.

RALPH S. PEIRCE, OF HINSDALE, ILLINOIS.

PIPE CLAMP.

Application filed October 11, 1920. Serial No. 416,166.

To all whom it may concern:

Be it known that I, RALPH S. PEIRCE, citizen of the United States, residing at Hinsdale, in the county of Du Page and State of Illinois, have invented a certain new and useful Improvement in Pipe Clamps, of which the following is a full, clear, concise, and exact description.

My invention relates to clamps which may be disposed about cylindrical objects such as water hose and other piping.

The invention has for one of its objects an improved form of clamp which may be used exclusively for the mechanical purpose of clamping and the invention has for another of its objects such a construction of the clamp that it may be effectively employed as a grounding clamp for electrically connecting circuit wiring with metallic piping.

The clamp of my invention employs an open circular band and a bridge piece having a laterally extending portion, there being also clamping means for assembling the ends of the band with the laterally extending portion of the bridge piece. My invention enables me to employ very thin metal for the band, the bridge piece itself being preferably of rigid formation where it engages the piping although the lateral extension of the bridge piece is preferably of U-form and somewhat resilient to enable the clamping bolt or other clamping means more readily to assemble the band and the bridge piece and also enabling the clamping of circuit wiring if the clamp is to be used for grounding the same.

I will explain my invention more fully by reference to the accompanying drawing showing the preferred embodiment thereof and in which Fig. 1 is a perspective view of a clamp; Fig. 2 is a cross sectional view thereof; and Fig. 3 is a perspective view of the component elements of the clamp in separated relation, the band being shown in the shape which it initially possesses before being clamped into position.

Like parts are indicated by similar characters of reference throughout the different figures.

The rigid metallic bridge piece has an arcuate portion 1 interposed between the metallic band 2 and the piping or other cylindrical object 3 to which the clamp is to be applied, the bridge piece being preferably formed of thick metal so as to make it sub-

stantially rigid where it engages the piping while the band 2 is made comparatively thin.

The bridge piece has a laterally extending portion 4 that is preferably of U-shape, this portion of U-shape having one end joined with the bridge piece and its other end directly free of the bridge piece. The circular band has two lateral extensions 5 and 6, the lateral extension 5 having a single bolt hole 7, a row of bolt holes 8 being arranged along the band at its other end, any of the latter bolt holes being adapted to be made complementary to the bolt hole 7 according to the size of the pipe surrounded by the band. Both sides of the U-shaped portion 4 are provided with aligned bolt holes 9. Where the extension 4 is of U-form the extension 5 is disposed between the sides thereof and the extension 6 is placed against the outer face of the side of the U-portion that is directly joined with the arcuate portion of the bridge piece. When the threaded shank of the metallic bolt 10 is passed through the holes 7 and 9 and the selected hole 8 in the band 2, the metallic bolt is turned to advance the nut 11 along the bolt stem toward the bolt head until the band 2 is brought to its final circular shape illustrated in Fig. 2.

The excess metal beyond the selected hole 8 in the band 2 may be removed by breakage as illustrated at 12 in Fig. 1.

Where the clamp is to be employed as a grounding clamp a current conducting wire 13 may be located in the bight of the U-shaped extension of the bridge piece, the bolt 10 serving to grip this wire between the sides of said U-shaped extension. A current conductor 14, that may be either directly connected with the conductor 13 or otherwise electrically associated, may be clamped between the metallic band and the free end of the U-shaped extension of the bridge piece as illustrated in Fig. 2. In order that the engagement between the band extension 5 and the bridge piece extension 4 may not be impaired when a conductor 14 is clamped as illustrated, the free end of the U-shaped extension may be angularly deflected away from the opposite side of the U-shaped extension as illustrated at 15. This angular deflection may be of any shape desired, the shape illustrated conforming to the curvature of the wire that is clamped between it and the corner that is formed by the circular portion of the band 2 and the extension 5.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

- 10 1. In a clamp, the combination with a bridge piece having an arcuate portion and a laterally extending outwardly projecting extension of U-shape joined at one end with one end of the arcuate portion of the bridge piece; of a circular band having two lateral outwardly projecting extensions, one between the sides of the U-portion and the other overlying the arcuate bridge portion; and a clamping bolt passing through passages that are formed in the lateral extensions of said band and bridge piece.
- 15 2. In a clamp, the combination with a bridge piece having an arcuate portion and a laterally extending outwardly projecting extension of U-shape joined at one end with one end of the arcuate portion of the bridge piece; of a circular band having two lateral outwardly projecting extensions, one between the sides of the U-portion and the other overlying the arcuate bridge portion; and a clamping bolt passing through passages that are formed in the lateral extensions of said band and bridge piece, the free end of the U-shaped extension having an angular continuation for the attachment of wire thereto.
- 20 3. In a clamp, the combination with a bridge piece having an arcuate portion and a laterally extending outwardly projecting extension of U-shape joined at one end with
- 25

one end of the arcuate portion of the bridge piece; of a circular band having two lateral outwardly projecting extensions, one between the sides of the U-portion and the other overlying the arcuate bridge portion; and a clamping bolt passing through passages that are formed in the lateral extensions of said band and bridge piece.

3. In a clamp, the combination with a bridge piece having an arcuate portion and a laterally extending outwardly projecting extension of U-shape joined at one end with one end of the arcuate portion of the bridge piece; of a circular band having two lateral outwardly projecting extensions, one between the sides of the U-portion and the other overlying the arcuate bridge portion; and a clamping bolt passing through passages that are formed in the lateral extensions of said band and bridge piece, said band having one bolt hole in one of its ends and a row of bolt openings arranged along the band at its other end.

In witness whereof, I hereunto subscribe my name this eighth day of October, A. D., 1920.

RALPH S. PEIRCE.
